UNITED STATES PATENT OFFICE.

WILFRID E. DIEGEL, OF RIVER ROUGE, MICHIGAN.

GAME.

Application filed July 29, 1925. Serial No. 46,742.

To all whom it may concern:

Be it known that WILFRID E. DIEGEL, a citizen of the United States, residing at River Rouge, in the county of Wayne and State of Michigan, has invented certain new and useful Improvements in Games, of which the following is a specification.

This invention is a game adapted to be played by two or more persons, individually or paired as partners; and the main object of the game is to provide an entertaining and instructive apparatus including a suitably stepped board having forty-eight holes therein representing the forty-eight States of the American Union, marbles to roll upon the said board, and differently colored stops for the several players, for filling the holes of the board after marbles lodge therein during the progress of the play.

Another object is to provide a game board having holes therein named after the several States of the American Union, marbles for the players successively to roll down the board, and differently colored stops for the various players to use in plugging up the holes into which the marbles roll during the course of their play—the purpose of the game being to see which player or which partners can count the most stops in the said holes after the holes are all plugged.

Other features of the game will appear in the course of the following specification with reference to the accompanying drawing, wherein

Figure 1 is a plan view of the board showing the lay-out of the game;

Figure 2 is a longitudinal, vertical section of the board;

Figure 3 is a detail of the trip-bar;

Figure 4 is a detail of one of the stops.

This game includes a specifically constructed box-like structure 1, made up of a rectangular base 2 enclosed by side boards 3 of a suitable height. A "flight" of steps 4 is arranged transversely within the structure 1, these steps rising successively above one another from the foot section 5 of the structure up to the opposite end 17. The upper surfaces of these steps are slightly sloped forwardly as clearly shown in Figure 2, so as to allow marbles readily to roll down from the uppermost step down onto the base 2. The foot section 5 of the base 2 adjacent the lowermost step is divided by a transverse strip 6 into a storage space 7 for idle

stops or plugs and a lodging space 8 for marbles in use. As here shown, six of the steps 4 are provided, and in the upper surface of each step are cut eight marble holes 9, making a total of forty-eight holes, or one for each of the forty-eight "United States". The holes 9 are preferably cut in staggered relation upon the successive steps, as shown in Figure 1. It is obvious that the number of steps, as well as the number of holes in each step, may be varied, so long as the total number of holes remains at forty-eight. Adjacent these forty-eight holes are to be printed the names of the States of the United States, so that each State is represented on the board by a hole properly designated. However, in addition to the forty-eight holes aforesaid, which may be termed "State holes", there are also cut upon certain of the steps two extra holes 10 and 11, adjacent one of which, as 10 is to be printed the words "Washington, D. C." and adjacent the other, as 11, the words "Lose one State." At the end 17 of the structure 4, is arranged a marble ledge 12, the upper surface of which also slopes forwardly to allow marbles placed thereon to roll off down the steps 4. A trip bar 13 is provided, the ends of which are bent sharply to one side, and is pivoted by pins 14 to the marble ledge 12 in such manner that the bar proper will lie along the outer or forward edge of the ledge 12, and yet may be readily raised, turning upon the pins 14, to allow marbles to roll thereunder and down the steps 4. A plurality of marbles 15 are provided. As here shown, six marbles are represented, but this number may be varied at will. These marbles are adapted to be positioned upon the ledge 12 back of the bar 13, where they rest until that bar is raised. There are finally provided one hundred stops or stop blocks 16, the same being divided into lots of twenty-five each, and each lot being colored a distinct color from the balance. By this arrangement, either two, three or four players may engage in the game, each player taking all the blocks of a certain color.

This game is played by each player successively placing all the marbles back of the bar 13 upon the ledge 12, and then raising the bar 13 and allowing the marbles 15 to roll down the steps 4. In their travel, one or more of them will fall into certain of the "State holes" 9; whereupon the player

plugs those holes with his stop blocks, which are permitted to remain therein to the end of the play. Each successive player repeats the process. Should any marble lodge in 5 the hole marked "Washington, D. C." the player is permitted to plug any vacant State hole he desires. Should a marble lodge in the hole marked "Lose one State", he must withdraw one of his stop-blocks from a 10 State hole theretofore plugged by him (if any). The holes 10 and 11 are never to be plugged. When all the State holes are plugged, the winner is determined by counting the plugs of the various colors in the 15 State holes. The predominating color wins the game. Of course, these rules may be varied should other States be added to the present group of United States, and the number of State holes would be increased ac- 20 cordingly.

While I have herein described a certain specific manner and method of constructing and assembling the elements of my invention, it is understood that I may vary from 25 the same in minor details, not departing from the spirit of my invention, so as best to construct a practical device for the purpose intended, as defined in the appended claims.

I claim:

30 1. A game, comprising in combination a box-like structure; a flight of steps arranged within the structure, the said steps having a plurality of marble holes cut in their upper surfaces; a marble ledge extended ad- 35 jacent the uppermost step; a trip bar pivot- ally mounted at the forward edge of the marble ledge; a plurality of stop-blocks adapted to fit into the said marble holes of the steps, the said blocks being divided into 40 a plurality of differentiated lots; and a plu-

rality of marbles for positioning back of the said trip bar, and adapted to roll down the said steps and to fall into the said marble holes, when the trip bar is raised.

2. A game, comprising in combination a 45 box-like structure; a series of steps mounted within the structure, there being cut in the upper surfaces of the steps a plurality of marble holes totaling the number of States in the United States of America; a marble 50 ledge adjacent the highest step of the series; a plurality of marbles adapted for positioning on the marble ledge; means for releasably holding the marbles upon the ledge; and a plurality of differently colored stop 55 blocks adapted to fit into the said marble holes of the series of steps.

3. A game, comprising in combination a box-like structure; a series of steps arranged within the structure, there being cut in the 60 upper faces of the steps a number of marble holes totaling the number of States in the United States of America, the said holes to be labeled and designated after the names of the said States, and two extra marble 65 holes, one of which is to be designated as "Washington, D. C." and the other by the phrase "Lose one State"; a plurality of stop-blocks adapted to fit into said marble holes, the said blocks being differentiated 70 by their coloring into a plurality of lots to accommodate a plurality of players; a plurality of marbles adapted to fit into the marble holes; and means for releasably holding the marbles in position adjacent the 75 upper step of the said series, so that when released they will roll down over the said steps.

In testimony whereof I affix my signature.

WILFRID E. DIEGEL.
